UNITED STATES PATENT OFFICE.

GEORGE H. FORSYTH, OF CHICAGO, ILLINOIS, ASSIGNOR TO MOTOR WHEEL CORPORATION, OF LANSING, MICHIGAN, A CORPORATION OF MICHIGAN.

DISK-WHEEL-HUB ASSEMBLY.

Original application filed March 24, 1922, Serial No. 546,272. Divided and this application filed January 16, 1925. Serial No. 2,793.

This invention relates to subject-matter divided out of my co-pending application Serial No. 546,272 filed March 24, 1922, and has to do primarily with the securing of an intimate disk-stressing assembly of the hub and disk.

According to the invention, the normal contours of the opposed faces of the disk and of the fixed and adjustable hub flanges are diverse to the extent that when the assembling bolts are tightened the contact is not at first uniform throughout, and, as the tightening of the bolts proceeds, the disk is deformed to a certain extent, slight but sufficient to maintain a stressed condition in the disk and a locking reaction on the bolts, whereby a secure fit at the hub and a strengthened disk body is attained.

Having reference to the drawings, Figs. 1 and 2 are fragmentary radial sections through disk wheels, illustrating embodiments of the invention in the hub portions thereof.

Having particular reference to Fig. 1 of the drawing the pressed steel hub 11 having an integral rear radially projecting flange 12 is assembled by means of the removable front flange or plate 13 and the bolts 14 with the single dished disk 15. It will be observed that the curvature of the central portion of the disk lying adjacent the flange 12 is slightly different from that of the flange at the point 16 with the result that as the hub flanges and disk are assembled contact is first obtained at 17 near the periphery of the flange 12 whereby the tightening of the bolts 14 serves to centrally stress the disk and to insure a firm bearing support at the point 17 for the disk.

In Fig. 2 of the drawing the cast or forged hub 27 is of similar construction being provided with the integral flange 28 and the removable flange or plate 29 between which the central portion of the disk 30 is

clamped by the bolts 31. As in the former case, the central portion of the disk and of the flanges is preferably such as to secure intimate firm contact at the point 32.

I claim:

1. In a disk wheel, the combination of a central hub portion, and a disk body portion, the wheel provided at the hub with a radially projecting disk supporting member, and means to clamp the disk to the supporting member, the contour of the overlapping portions of the disk and supporting member being diverse to the extent that when brought together the disk will first contact the support non-uniformly and be slightly deformed under force ultimately applied to effect and maintain a tight fit under stress.

2. In a wheel, the combination of a central hub portion, and a disk body portion, the wheel provided at the hub with a radially projecting disk supporting member, the contour of the overlapping portions of the disk and supporting member being diverse to the extent that when forced together the disk will first contact the peripheral portion of the support and be slightly deformed to effect and maintain a tight fit under stress.

3. In a wheel, the combination of a central hub portion, and a disk body portion, the disk body at the hub clamped between front and rear supporting members projecting radially from the hub proper into overlapping relation with the disk, the contour of the overlapping disk and supporting members being diverse to the extent that when forced together the disk will first contact with the peripheral portions of the supporting members and be slightly deformed to effect and maintain a tight fit under stress.

In testimony whereof I have hereunto subscribed my name.

GEORGE H. FORSYTH.
